United States Patent Office.

JAMES RICKARD AND JOHN COOK, OF PHILADELPHIA, PENNSYLVANIA.

Letters Patent No. 62,973, dated March 19, 1867.

IMPROVED BED BOTTOM.

The Schedule referred to in these Letters Patent and making part of the same.

TO ALL WHOM IT MAY CONCERN:

Be it known that we, JAMES RICKARD and JOHN COOK, of Philadelphia, Pennsylvania, have invented certain Improvements in Bedsteads; and we do hereby declare the following to be a full, clear, and exact description of the same, reference being had to the accompanying drawing, and to the letters of reference marked thereon.

Our invention consists of certain devices fully described hereafter, whereby the parts which compose the spring bottom of a bedstead, may be readily secured to or detached from each other.

In order to enable others skilled in the art to make our invention, we will now proceed to describe the mode of constructing the same, reference being had to the accompanying drawing, which forms a part of this specification, and in which—

Figure 1 is a sectional elevation of a bedstead with our improvements.

Figure 2, a plan view of part of the bedstead.

Figure 3, an end view looking in the direction of the arrow, fig. 2; and

Figure 4, a detached plan view of part of the bedstead, drawn to an enlarged scale.

A A are the posts, B B the end rails, and C C the side rails of a bedstead, and on the end rails B B bear the ends of the side rails a a' of an oblong detachable frame, D. At the inner side of each rail a a' are secured dove-tailed metal sockets, d d, open at the top to permit the insertion of the dove-tailed ends of the transverse rails b b' of the frame D. Each rail b consists of two strips, x x', fig. 4, which are screwed together, and between which are inserted, so as to hold firmly, the outer ends of springs, c, consisting of strips of steel curved as shown in the drawing, the inner end of each spring being jointed to a ring, e, fitted to the end of a flexible slat, h, which projects through the ring and bears on the spring. A number of these slats are thus connected to the transverse rails b and b' of the detachable frame D. The slats being flexible and resting on flexible springs afford a yielding and elastic support for a bed or mattress. As the weight upon the bed is increased the springs c c will be flattened and will be brought to a greater extent in contact with the slats, the rigidity of the springs being thus increased so that the slats are prevented from sinking too far. Any one of the slats may be easily removed without disturbing the others by elevating one end and slipping off the ring jointed to the adjacent spring, the opposite end being then withdrawn from the opposite ring and the whole of the parts may be disconnected from each other by separating the two parts x x' of each strip b b' to allow the springs c c to be detached. By the use of the dove-tailed sockets d d, in connection with bars or strips b b, having dove-tailed ends, the securing together of the side and end pieces of the frame D is facilitated and the parts are held firmly together and may be readily disconnected without the necessity of resorting to tedious manipulation with tools. The springs c c, instead of being secured to a detachable frame, D, may be attached to the end rails of the bedstead.

We claim as our invention, and desire to secure by Letters Patent—

The strips b and b', having dove-tailed ends adapted to dove-tailed sockets d, in combination with the springs c c and slats h, substantially as described.

In testimony whereof we have signed our names to this specification in the presence of two subscribing witnesses.

J. RICKARD,
J. COOK.
